UNITED STATES PATENT OFFICE

160,418

PIANO CASE OR THE LIKE

Emil H. Orenick, Parma, Ohio

Application February 23, 1950, Serial No. 8,089

Term of patent 14 years

(Cl. D56—9)

To all whom it may concern:

Be it known that I, Emil H. Orenick, a citizen of the United States, residing in the city of Parma, county of Cuyahoga and State of Ohio, have invented a new, original, and ornamental Design for a Piano Case or the Like, of which the following is a specification, reference being had to the accompanying drawing, forming a part hereof.

I claim:

The ornamental design for a piano case or the like, substantially as shown.

EMIL H. ORENICK.
